MEANS FOR PRODUCING A NECK FINISH
WITH A THREAD HANG-UPNorman R. Beck, Baltimore, Md., assignor to
Carr-Lowrey Glass Co., Baltimore, Md.

Application May 9, 1935, Serial No. 20,657

1 Claim. (Cl. 49—69)

This invention relates to a means for producing a bottle or other glass container the neck finish of which is provided with a thread hang-up.

As is well known to those skilled in the art of bottle manufacture, it has been necessary heretofore, in the manufacture of glass bottles and the like in gob machines, to provide the neck finish with either a ball hang-up, an undercut hang-up, or a hang-up in the form of a concealed ball. All of these hang-ups have been objectionable for one reason or another. In the first place a ball hang-up mars the appearance of the neck finish in that it constitutes an annular enlargement necessitating a longer neck than would be required otherwise. An undercut hang-up tends to weaken the neck finish and frequently in the manufacture of bottles with a hang-up of this type, the orifice in the neck has been choked and interfered with the proper use of the bottle for the purpose intended. Where a concealed ball is used as a hang-up a very long cap is required as a closure for the purpose of concealing the ball, this cap generally extending down to the shoulder portion of the bottle.

While it has been possible heretofore to produce in suction machines, glass bottles and other containers with threaded neck finishes and without ball or undercut hang-ups, this being due to the fact that the neck ring travels with the bottle through every stage of its formation, the same advantageous results have not been obtainable with gob machines wherein the neck ring leaves the parison immediately following the transfer thereof from the blank mold to the blow mold.

Heretofore in such machines, in order to prevent the neck finish from becoming distorted by settling in the blow mold prior to the blowing operation, some type of hang-up such as a ball or an undercut has been necessary in addition to the thread finish produced in the neck ring.

An object of the present invention is to provide a means whereby the neck portion of a parison, when formed with a thread finish in a gob machine, need not be formed with an additional portion for use as a hang-up but the thread finish, on the contrary, will constitute an efficient hang-up for supporting the neck finish in proper position in the blow mold to which the parison has been transferred, thereby allowing the production of bottles or the like having short necks with thread finishes and without supplemental hang-ups.

With the foregoing and other objects in view which will appear as the description proceeds the invention resides in certain novel details of con-

struction and combinations of parts hereinafter more fully described and pointed out in the claims, it being understood that changes may be made without departing from the spirit of the invention or the scope of the appended claims.

In the accompanying drawings have been shown the several steps essential to the production in a gob machine of a glass bottle or the like having a thread hang-up.

In said drawings Figure 1 is a section through portions of an open blow mold to which a parison has been transferred by a neck ring, the neck ring being shown in position directly over the blow mold following the transfer of the parison but prior to the closing of the mold and the removal of the neck ring.

Figure 2 is a view similar to Figure 1 showing the members of the blow mold closed about the parison prior to the removal of the neck ring.

Figure 3 is a similar view following the removal of the neck ring and release of the parison which has gravitated into such position as to cause the thread of its neck finish to constitute a hang-up.

Figure 4 is a section on the line 4—4, Figure 3 following the completion of the blowing operation and the opening of the blow mold, the take-out plates being shown in engagement with the neck finish as a preliminary step toward removing the finished bottle or the like from the machine.

Figure 5 is a plan view of portions of the blow mold showing the seat surrounding the neck opening for engagement with the thread hang-up.

Figure 6 is a section through the upper portion of the blow mold taken on the line 6—6, Figure 5.

Referring to the figures by characters of reference 1 and 2 designate the opposed members of the blow mold of a gob machine, these members, when brought together as in Figures 2, 3 and 5, cooperating to form a cavity 3 therebetween for the reception of a parison P and the subsequent shaping of the finished bottle or other container B. The members 1 and 2 also cooperate at their upper ends to form a neck opening 4 therebetween adapted to receive the neck finish N of the parison.

The ordinary neck ring of a gob machine has been indicated at 5 and is used not only for shaping the neck finish after the gob has been deposited in the blank mold, but also for transferring the parison from the blank mold to the open blow mold, it being understood that upon the completion of this transfer the neck ring will fit snugly on the top of the blow mold as

shown, at the same time supporting the parison in properly centered position in the blow mold.

The neck ring 5 is designed to form a thread finish T on the neck of the parison, this thread 5 having any desired number of convolutions.

The opening 4 is enlarged at its upper end to provide a spiral seat 6 extending once around the opening with its ends terminating at the upper and lower ends respectively of a shoulder 10 or abutment 7 as shown particularly in Figure 6. The seat 6 has the same pitch as the lower convolution of the thread T and the shoulder 7 formed by the seat is located where it will be directly under the lower end of thread T when 15 the mold is closed.

With the blow mold formed as described and the parison provided with a neck finish having a thread properly pitched with respect to the seat 6, it will be apparent that the following 20 operations in the formation of the bottle or the like will take place in succession: The neck finish T will be formed in the neck ring in the usual manner after the gob has been deposited in the blank mold and then blown to produce a parison; thereafter the neck ring will transfer the parison P to the open blow mold where it will be suspended by the neck ring in a properly 25 centered position as shown in Figure 1; the mold will then close about the neck finish as shown 30 in Figure 2 while the parison is still being supported by the neck ring and immediately following the closing of the mold the neck ring will open and move back to its initial position in the machine, thereby releasing the neck finish 35 which will drop by gravity a distance slightly greater than the width of a thread until the lower convolution of the thread T comes into contact with the correspondingly pitched seat 6 as shown in Figure 3.

40 The seat and the lower convolution of the thread will cooperate to support the parison in

vertical position without distortion and as efficiently as though an ordinary ball hang-up had been employed. It will be noted that when the thread T is on the seat 6 the end thereof will be held in contact with the shoulder 7 so that there is no danger of the parison rotating on its seat. 5

Following the positioning of the thread hang-up on its seat 6 the usual blow head is brought to position on the mold and the blowing of the 10 bottle is completed.

It will be understood of course that by utilizing the means stated, it becomes possible to produce in a gob machine a bottle or other glass container utilizing the thread of its neck finish as 15 a hang-up so that it becomes unnecessary to form the neck with an unsightly ball hang-up, or a weakening undercut hang-up. On the contrary a very short neck with a thread finish can be produced on machines in which such production has heretofore been impossible. A further advantage resulting from the use of this invention is found in the fact that when the thread finish is seated in the enlarged upper end portion of the neck opening in the mold, 20 the thread on the neck of the parison extends up to the wall of the opening, as shown in Figure 3. Thus there is no danger of distorting this portion of the neck finish (which is the hottest and softest) when the air is blown through the neck 25 into the suspended parison. 30

What is claimed is:

A blow mold for a glass forming machine having a neck opening with an enlarged upper end portion, and a helical shoulder at the bottom of 35 the enlarged portion of the opening, said shoulder being pitched to correspond with the pitch of the lower convolution of a threaded neck finish and providing a seat for said convolution.
